UNITED STATES PATENT OFFICE.

ISAAC E. PALMER, OF MIDDLETOWN, CONNECTICUT, ASSIGNOR TO THE I. E. PALMER CO., OF MIDDLETOWN, CONNECTICUT, A CORPORATION OF CONNECTICUT.

HEAD AND SHOULDER REST OR SUPPORT FOR COUCH AND OTHER HAMMOCKS.

972,712.

Specification of Letters Patent. Patented Oct. 11, 1910.

Application filed June 16, 1910. Serial No. 567,123.

To all whom it may concern:

Be it known that I, ISAAC E. PALMER, a citizen of the United States, and a resident of Middletown, in the county of Middlesex and State of Connecticut, have invented an Improvement in Head and Shoulder Rests or Supports for Couch and other Hammocks, of which the following description, in connection with the accompanying drawings, is a specification, like letters on the drawings representing like parts.

This invention relates to head and shoulder rests or supports for couch and other hammocks and is in part a division of my co-pending application No. 547,637, filed March 7, 1910, and is in its entirety a continuation thereof.

In order that the principle of the invention may be readily understood, I have disclosed certain embodiments thereof in the accompanying drawings, wherein—

Figure 1 is a side elevation of a couch hammock embodying my invention; Fig. 2 is a detail on a larger scale of a portion of the construction shown in Fig. 1; Figs. 3 and 4 are side elevations of the head end of a couch hammock showing the head support flat upon the body of the hammock; Fig. 5 is a view partially in side elevation and partially in vertical section of a slightly modified form of my invention; Fig. 6 is a detail showing the manner of attaching to the head suspension end the form of head support shown in Fig. 5; Fig. 7 is a plan view, and Fig. 8 is a side elevation of a head support of a less length than the body portion of the hammock; Figs. 9 and 10 are respectively a plan view partially broken away and a partial side elevation of a slightly modified form of my invention; Figs. 11, 12 and 13 are perspective views of additional forms of my invention; Fig. 14 is a side elevation partially in section showing my invention applied to a hammock in which the body passes under end cross bars; and Fig. 15 is a detail showing means for maintaining the hammock body transversely taut.

Couch hammocks have been provided with frames, one end of which may be adjusted at an inclination to the remainder thereof, so as to support the head and shoulders in inclined position, such, for example, as shown in U. S. Patent to Draper, No. 906,120, December 8, 1908.

My present invention relates to attach-

ments for couch and other hammocks or other suspended structures adapted to support the head and shoulders of the user in inclined position; said attachment being structurally separate from the frame of the couch hammock and being in the preferred embodiment thereof an attachment to be readily applied to the couch or other hammock. In certain embodiments of the invention, and when used with a couch hammock, this attachment serves as a combined head support and mattress cover and may be employed for either purpose or for both purposes conjointly.

Referring more particularly to the drawings and first to that form of my invention shown in Figs. 1 to 4 inclusive, the body portion of a couch hammock to which my invention may be applied, is shown at 1, a portion of the frame at 2, the suspension ends at 3—3 and their spreaders at 4—4. The said suspension ends are preferably of cloth and therefore are flexible and may yield relatively to and longitudinally of the frame or body portion of the hammock when the latter is suspended. Each spreader 4 is preferably inserted in a pocket 5, and the usual hammock suspension cords are attached to said spreaders in any suitable manner. The body portion of the hammock receives thereon the mattress 6. I have not herein attempted to illustrate other types of hammocks or other suspended structures to which my invention may be applied.

In Figs. 1, 3 and 4, the head support is represented at 7 and in this form of my invention constitutes also a mattress cover. Said support is composed of a strip of suitable flexible material, and preferably in nature similar to that constituting the hammock body. It is provided with suitable means for attaching it, preferably detachably, to the head suspension end. Preferably I provide a series of hooks 8 of metal bent into the shape shown and adapted to straddle the spreader 4. Each hook is provided with an eye 9, to which is attached the head support 7 in any suitable manner, as by means of links 10 engaging eyes 11 secured at suitable points along the spreader 12 in a hem or pocket 13 at the end of said support. If desired, said support may have attached thereto a suitable pillow 14. I have also indicated a second spreader 15 applied to said head support below the pil-

low 14. It is, of course, evident that more than one pillow may be attached to or employed in conjunction with said head support. In that form of my invention shown in Fig. 1, said head support serves also as a mattress cover and therefore is of sufficient length to extend when suspended from the head suspension end to the foot suspension end of a hammock where it may be provided with a spreader 16 which may be tucked in if desired between the foot suspension end and the end of the mattress.

In use the hammock occupant lies upon the strip 7, and his body holds the same in the position shown so as to support his head and shoulders at a suitable inclination, which it is evident may be varied as desired. If it be not desired to use the strip 7 as a means for supporting the head and shoulders in inclined position, the hooks 8 may be detached from the head suspension end 3 and the head end of the strip may be folded as shown in Figs. 3 or 4 with the pillow 14 above or below the body of the strip, so as to serve as the usual pillow. It will be observed that the strip 7 is of such length as to extend from the foot suspension end to the spreader 4 of the head suspension end, or sufficiently close thereto to be suspended therefrom. The strip 7 is attached to the edge suspension end 3 at a suitable number of points transversely thereof and contacts therewith at a number of points along the same, and in the use of the attachment it yields with the yielding movement of the head suspension end. In other words, the swinging movements of the head suspension end 3 are partaken of by said attachment, so that the head and shoulders of the user are supported in easy and comfortable position at all times.

The head support may be suspended from the suspension end 3 of the hammock by attaching it in any suitable manner and the support itself may be varied in character. In Fig. 5, I have represented a head support 17 having attached thereto three pillows 18, 19, 20, the pillow 20 being particularly intended to receive the hips of the user to prevent him sliding along the hammock, which might occur owing to the inclined position of his head and shoulders, were not some suitable pillow or other projection provided. In this form of the invention the upper end of the strip 17 is provided with a spreader 21 adapted to be attached to the head suspension end 3 by means of bolts 22 which may be placed in any one of the holes 25 shown in Fig. 6, thereby providing for suitable vertical adjustment of the attachment. This form or type of my invention having a hip-receiving pillow, is peculiarly adapted to hammocks not of the couch type.

The head support 26 shown in Figs. 7 and 8 is preferably similar to that shown in

Figs. 1 to 4 inclusive, excepting for the fact that it is of materially less length than the hammock body and does not in this case serve as a mattress cover. It is provided with a pillow 27 at its upper end and with a pillow 28 at its lower end, the function whereof is similar to the pillow 20 shown in Fig. 5. The length of the support shown in Figs. 7 and 8 is preferably sufficient for the reception of the entire person of the user from the hips upward, so that the weight of the occupant will hold the head support in place as previously described. As already stated, this form or type of my invention having the hip-receiving pillow is peculiarly adapted to hammocks not of the couch type. Within the scope of my invention the strip is used also as a mattress cover and may be positively attached to the foot suspension end in any suitable manner, as for example by lacing 28' shown in Figs. 9 and 10 as passing through gromet eyes 28" in the foot suspension end and in the end of the strip 28''. Ordinarily it is sufficient to provide the foot end of the said cover with a spreader which may be tucked in as described at the end of the mattress, but such spreader may be omitted.

In Fig. 11, I have shown a simple form of my invention wherein the couch hammock is of the usual structure, such as indicated in Fig. 1. I apply thereto a strip 29 which itself may be a hammock body provided at its ends with the usual spreaders 30 and suspension cords 31. It will be apparent that one end of this supplemental hammock 29 may be attached to the support 32 from which the head end of the couch hammock is suspended, in which event the supplemental hammock serves as a head support and also as a mattress cover. The foot end of the supplemental hammock may be rolled up at the foot end of the couch hammock.

In Fig. 12, I have shown a slightly modified form of my invention wherein the mattress 33 is itself provided with means such as cords 34 and hooks 35 for supporting the head end in inclined position in a manner similar to that shown in Fig. 1. In this form of my invention, the mattress may if desired be provided with a reinforcing bottom, to which the cords 34 are attached.

In Fig. 13, I have shown a slightly modified form of the invention and differing from that form shown in Fig. 8, mainly in that I have provided means positively to attach the foot end of the head support 36 to a couch hammock. For this purpose, I may provide any suitable means, such, for example, as pins 37 to engage any suitable holes 38 provided in the frame 39 of the hammock. The holes may be so arranged as to permit longitudinal adjustment of the strip.

It will be apparent from the foregoing de-

scription that I have provided an attachment to be applied to an ordinary couch hammock without requiring any change in the structure of the latter. This attachment 5 may be used either as a head support or as a mattress cover only, or both functions may be utilized conjointly. The weight of the occupant holds the head support in inclined position and the angle of inclination may be 10 varied in an obvious manner. It is, of course, evident that I may employ pillows distinct from the head support and placed for example underneath the same to be received at the small of the back.

15 It is, of course, obvious that my invention may be applied to various types of couch or other hammocks. It is unnecessary to illustrate all the types of hammocks to which the invention may be applied, but in Fig. 20 14 I have represented the so-called Utopia hammock. The frame is provided with side members 40 and end members 40' and with brackets 41 in which are seated end cross rods 42. The hammock body 43 overlies the 25 frame and passes under said end cross bars and thence to the points of support. The upstanding ends 44 are therefore unitary with the body 43. The head support is shown at 45 and is preferably substantially 30 similar to that shown in Fig. 1. It is herein represented as formed of suitable fabric or other flexible material and provided at its upper end with a spreader 46, to which hooks 47, straddling the spreader 48 of the 35 suspension end, are connected by links 49. Preferably the pillow 50 is secured to the support. Preferably the head support is sewed or otherwise attached to the hammock body as indicated at 51. This head support 40 may be of any desired length, but need not extend substantially beyond the point of union with the body 43. If desired, however, the lower end of the head support need not be attached to but may merely rest upon 45 the body 43. When the hooks 47 have been detached from the suspension end 44, the head support 45 may be positioned flat upon the hammock body and the pillow 50 would then lie flatwise upon the body, the spreader 50 46, links 49 and hooks 47 being tucked in between the suspension end and the pillow.

I contemplate the provision of means not claimed in this application for maintaining laterally taut couch hammocks in which the 55 body overlies the frame, as in the Utopia hammock. In such case, I provide movable members 52 pivoted at 53 to and adjacent each end of each side bar 40. These members are preferably metallic and are of any 60 suitable form. They are intended when turned into a substantially upright position to be inserted into pockets or hems 54 formed in or applied to the lateral edges of the hammock body near the ends of the frame. 65 After these members have been inserted in

the pockets they are folded down and so lie flat against the frame. Preferably they extend substantially to or even beyond the end members 40' of the frame and so hold transversely taut the hammock body at the 70 ends. This insures the proper position of the lateral edges of the body from end to end of the frame. This hammock body tensioning means may be employed with or without the head rest.

75 The support herein disclosed and particularly that form thereof having a shoulder supporting pillow, or both a shoulder supporting pillow and a body supporting or bracing pillow to be positioned at the hips 80 of the hammock occupant, may be applied to hammocks not of the couch hammock type by attaching the support to such ordinary hammock at or adjacent the suspension end thereof. Such support may be employed in 85 conjunction with the ordinary pillow attached to and forming a part of the ordinary hammock to support the head of the occupant.

Having thus described one illustrative embodiment of my invention, I desire it to be understood that although specific terms are employed, they are used in a generic and descriptive sense and not for purposes of limitation, the scope of the invention being 95 set forth in the following claims.

Claims:

1. A head and shoulder rest or support for an ordinary couch hammock or the like having an upright head end and a substantially 100 flat body portion, said rest or support consisting of a cloth strip having means for suspending the same at the head suspension end of the hammock, said strip extending at a downward inclination beneath the head 105 and shoulders of the occupant, and along the substantially flat body portion of the hammock and terminating between the hips and knees of the user, whereby said support may be held in place by the body of the user. 110

2. A head rest or support for a couch hammock having a substantially flat body portion and upright suspension ends, said rest or support being adapted to extend at a downward inclination beneath the head 115 and shoulders of the user, said support having along its upper portion hooks flexibly connected thereto to engage said head suspension end.

3. A head rest or support for a couch 120 hammock having a substantially flat body portion and upright suspension ends, said rest or support being adapted to extend at a downward inclination beneath the head and shoulders of the user, said support having hooks pivoted along its upper portion transversely thereof, whereby it may be suspended along said head suspension end.

4. A head rest or support for a couch 125 hammock having a substantially flat body 130

- portion and upright suspension ends, whereof the head suspension end has at its upper edge a transverse spreader, said rest or support being adapted to extend at a downward inclination beneath the head and shoulders of the user and inverted U-shaped hooks attached at transverse intervals along the upper portion of said rest or support and adapted to fit snugly over said spreader and 10 brace the support in position.
5. A head rest or support for a couch hammock having a substantially flat body portion and upright suspension ends, said rest or support being adapted to extend at 15 a downward inclination beneath the head and shoulders of the user, said support having along its upper portion suspension hooks and links connecting said hooks to said support.
- 20 6. A head and shoulder rest or support for couch or other hammocks or the like, said rest or support being composed of a substantially plane flexible body having means for suspending the same adjacent the 25 head suspension end of a hammock, so as to extend at a downward inclination beneath the head and shoulders of the user when lying upon the hammock, said rest or support extending sufficiently along and in contact with the body-receiving portion of the 30 hammock to receive thereon the hips of the user, whereby said rest or support may be held in place upon the body-receiving portion of the hammock merely by the body of 35 the user, the foot end of said rest or support normally having longitudinal play along the hammock, to vary the angle of inclination of the rest or support or the position of said foot-end.
- 40 7. A head and shoulder rest or support for a couch hammock having a substantially flat body portion and upright suspension ends, said rest or support extending from the head suspension end of the hammock 45 at a downward inclination beneath the head and shoulders of the user to and having longitudinal play along said flat body portion, said rest or support having a transverse spreader extending along its upper end portion closely adjacent the head-receiving portion thereof, and means for holding said spreader in substantially fixed relation with respect to said head suspension end adjacent the head of the user.
- 55 8. A head and shoulder rest or support for an ordinary couch hammock having an upright head end and a substantially flat body portion, said rest or support consisting of a substantially plane head and shoulder-receiving strip having means for suspending the same at the head suspension end of said ordinary couch hammock without special construction of said hammock, and extending in use at a downward inclination beneath the head and shoulders of the user, 60 the lower end of said support normally having longitudinal play along the flat body portion of the hammock, whereby said support may, in periods of non-use, be positioned vertically at and against the inner 70 face of the head suspension end of the ordinary couch hammock, and in periods of use be adjusted at varying angles to the couch hammock head end.
9. A head and shoulder rest or support 75 for a couch or other hammock consisting of a flexible strip having at its head end means for suspending the same at the head suspension end of the hammock, said strip being substantially plane throughout its extent 80 and extending at a downward angle to the flat or body receiving portion of the hammock and having fixed thereto a hip-receiving bracing pillow, said strip and pillow being adjustable to varying positions and held 85 in adjusted position by the body of the user engaging said pillow.
10. An attachment for ordinary couch hammocks having a flat body portion and upright suspension ends, said attachment 90 consisting of a head and shoulder-supporting strip extending at a downward inclination beneath the head and shoulders of the user, said strip having means adjacent the head-receiving portion thereof for securing 95 the upper end of the same flatwise against the inner face of the head suspension end of such ordinary couch hammock and in substantially fixed relation thereto, the lower end of said support normally extending to 100 the flat portion of the hammock and having longitudinal play along the same, whereby said support may be readily applied to and removed from the head suspension means and adjusted at varying angles to an ordinary couch hammock without modification 105 of the latter.
11. An attachment for ordinary couch hammocks having a flat body portion and upright suspension ends, said attachment 110 consisting of a cloth strip constituting a head and shoulder-rest or support adapted to extend at a downward inclination beneath the head and shoulders of the user, said cloth strip having means adjacent the head-supporting portion thereof for suspending the upper end of the same at the head suspension end of said ordinary couch hammock and in substantially fixed relation to 115 said head suspension end, the lower end of said cloth strip normally extending to the flat portion of the hammock and normally having longitudinal play along the same, whereby said cloth strip may be readily applied to and removed from its position at 120 the head suspension end of an ordinary cloth hammock and be adjusted at varying angles with relation to said flat body portion without modification of said hammock.
12. A flexible head and shoulder rest or 125

support for a couch hammock having a frame providing a substantially flat body portion and upright suspension ends, said rest or support being a substantially plane strip suspended directly and wholly from the head suspension means of such couch hammock, said head and shoulder rest extending at a downward inclination to the flat body portion of the hammock so as to receive thereon the head and shoulders of the user and permit the limbs to be extended along the flat body portion of the hammock, said rest or support having means for suspending the same at the head suspension end, said suspension means being readily detachable from the point of suspension, and said rest or support being, when detached, positionable flatwise along the flat

body portion of the hammock so as to extend from the base of said flexible head suspending end flatwise along and in contact with the same beneath the body of the hammock's occupant without presenting obstructions thereto, said rest or support having longitudinal play along said flat portion of the hammock for presenting different adjustments to the head and shoulders of the user.

In testimony whereof, I have signed my name to this specification, in the presence of two subscribing witnesses.

ISAAC E. PALMER.
